UNITED STATES PATENT OFFICE.

CHRISTOPHER WINKEL, OF BELVIDERE, ILLINOIS, ASSIGNOR TO NATIONAL SEWING MACHINE COMPANY, OF BELVIDERE, ILLINOIS, A CORPORATION OF ILLINOIS.

REVOLVING-HOOK SEWING-MACHINE.

1,049,791.

Specification of Letters Patent.

Patented Jan. 7, 1913.

Application filed December 21, 1903. Serial No. 185,976.

To all whom it may concern:

Be it known that I, CHRISTOPHER WINKEL, a citizen of the United States, residing at Belvidere, in the county of Boone and State 5 of Illinois, have invented certain new and useful Improvements in Revolving-Hook Sewing-Machines, of which the following is a full, clear, and exact specification.

My invention relates to that class of sewing machines in which a rotary hook is revolved around the bobbin, or other suitable supply of lower thread, by connection with suitable rotating means, such as a shaft, and the invention has for one of its 10 important objects to prevent the thread from becoming wound around such shaft or rotating means or the part which connects the same with the hook, or otherwise becoming entangled with the hook mechanism. 15 should the operator fail to arrange it properly when starting to sew or rotate the machine in the wrong direction. A serious and well known objection to this form of sewing machines is that the hook produces 20 a twist in the loop, which often results in the formation of knots or snarls when the take up acts to tighten the loop or the loop 25 is drawn upward by any other means. This invention is designed to avoid this defect, 30 and it therefore has for its further object to untwist the loop before it is drawn up or tightened. In this form of machine, the lower thread, where it passes from the tension device of the bobbin to the passage in 35 the throat plate, ordinarily extends at an oblique angle while under the tension of the bobbin, and the loop of upper thread, in the act of being drawn up, has to force its way between the throat plate and this taut lower 40 thread, and this results in great friction on the upper thread, often causing it to break, and in any event making the stitching tight or loose according to the speed, and resulting in uneven sewing.

To overcome this defect, this invention 45 has for one of its objects to unwind sufficient slack of the lower thread, before the loop is drawn up, to relieve the same of undue strain at such time, and hence avoid 50 undue friction on the upper thread. And this invention has for its object generally to combine all the advantages of both the revolving hook and the rotary shuttle forms of sewing machines with practically all of

their disadvantages and objectionable features eliminated.

With these ends in view, my invention consists in certain features of novelty in the construction, combination and arrangement of parts by which the said objects and certain other objects hereinafter appearing are attained, all as fully described with reference to the accompanying drawings and more particularly pointed out in the claims.

In the said drawings—Figure 1 is a front 65 elevation of a part of a sewing machine head provided with these improvements. Fig. 2 is a bottom view thereof. Figs. 3 to 9, inclusive, are details of the rotary hook, the bobbin and the bobbin case, Fig. 3 being 70 a cross section of the flange and crank plate which connects the shaft to the hook, Fig. 4 a cross section of the bearing ring for the hook, Fig. 5 a side or edge elevation of one 75 part of the hook proper in which the bobbin case cavity is formed, Fig. 6 a side elevation of the bobbin case and its support with the parts separated, Fig. 7 a side or edge elevation of the cap which holds the bobbin case support in the hook cavity, Fig. 8 a front 80 elevation of the member shown in Fig. 5, and Fig. 9 a front elevation of the member shown on the left in Fig. 6. Fig. 10 is a top or plan view of the parts assembled, the 85 sewing machine bed plate being removed. Fig. 11 is a front elevation of the parts shown in Figs. 3 to 7 assembled with the removable part of the bobbin case omitted, also showing the point of the hook in the 90 act of carrying the loop around the bobbin case. Fig. 12 is a similar view, showing the point of the hook still farther advanced with the loop. Fig. 13 is a vertical cross section on the line 13—13, Fig. 12. Fig. 14 is a 95 vertical section of all of the parts shown in Figs. 3 to 9, assembled and with the bobbin in place. Fig. 14^a is an enlarged detail elevation, showing the arrangement of the thread with relation to the bobbin, and also illustrating the bobbin lock. Fig. 15 is a 100 plan view of the bobbin case proper. Fig. 16 is a diagrammatic view showing the point of the hook in the act of taking the loop. Fig. 17 is a plan view of a part of the hook and the bobbin case support, showing the 105 point of the hook advanced into the loop and pulling one side of the loop into the thread seat or notch in the bobbin case sup-

port. Fig. 18 is a vertical section of the construction illustrated in Fig. 17. Fig. 19 is a view showing the point of the hook still farther advanced and producing the twist in the loop, this view being taken from the side of the machine toward which the hook rotates, on the side opposite the operator. Fig. 20 is a view taken from the opposite side, showing the hook mechanism and connected parts in vertical section with the bobbin case support in elevation and the loop extending therearound, also illustrating the needle and the relation of the loop to the bobbin thread, this latter view being taken 15 with the point of the hook a quarter turn farther advanced than the position in Fig. 19, and Fig. 21 is a view similar to Fig. 20, with the point of the hook advanced a still farther quarter turn, or about three-quarters 20 from the start, showing how the finger un- twists the loop.

1 is the bed plate of the sewing machine head, 2 the needle, 3 the throat plate through which the needle passes, and 4 the 25 upper or needle thread, all of which may be of the usual or any suitable construction, the feed, which may be of any ordinary or desirable form, being omitted for the sake of clearness and as it constitutes no part of the 30 present invention.

5 is the rotary shaft, which may be driven in any suitable way and mounted under the bed plate 1 in the usual or any suitable bearings, not necessary to illustrate, and contiguous to the end of this shaft is arranged a 35 wall or plate 6, which extends downwardly from the under side of the bed plate 1 in a vertical plane, or a plane at right angles to the shaft 5, and to the end that it may be 40 firmly secured and closely fitted to the under side of the bed plate it is provided with lugs 7 on each side through which pass screws, or other attaching devices, 8, threaded in bosses 9 on the under side of the bed plate 45 1. This plate 6 is in the form of a ring and its upper side is cut away on the chord of a circle where it meets and contacts with the lower side of the throat plate 3, as better shown in Fig. 1, it being extended upwardly 50 between the opposite ends of the bosses 9 so as to fit accurately against the throat plate 3, and thereby constitute a complete wall or barrier to prevent the thread from being carried to its inner side and wound around or 55 entangled with the shaft 5, or parts connected therewith. The plate 6 is recessed in its outer face as more clearly shown in Fig. 20, and in this recess is seated a ring 10, which is also segregated flush with the upper 60 end of the plate 6, so as to come against the under side of the throat plate 3 and at the same time prevent the ring 10 from rotating in its recess, the face of the ring 10 being flush with the face of plate 6. The plate 6 65 is formed with a circular aperture 11, which

is of greater diameter than the inner periphery of the ring 10, so that the ring 10 will constitute a flange projecting over the edge of this opening 11, as shown in Fig. 20, and within the ring 10 is arranged a journal 12 formed on the body portion 13 of the rotary hook, which will presently be described more in detail. The back of this body portion 13 fits accurately against the face of ring 10, while the end of the journal 12 comes flush, or substantially flush, with the inner face of the ring 10, and secured thereto is a ring 14 which overlaps the ring 10 and thereby constitutes a means of holding the journal 12 against movement in a direction 70 lengthwise of its axis while permitting the journal 12 to revolve freely within its journal bearing constituted by the inner periphery of the ring 10. The body 13 of the hook may be thus revolved in its independent bearing by the aid of any suitable connection with the shaft 5; for example, the end of the shaft may be provided with a slotted crank arm 15 in the slot of which 75 engages a wrist 16 secured to the ring 14, or to any other connection on the body 13, so that as the shaft revolves the body of the hook will be rotated accordingly, but this peculiar form of connection will not be described in detail herein as it constitutes the 80 subject-matter of a co-pending application, Serial No. 189,397, filed January 18th, 1904.

As more clearly illustrated in Fig. 5, the body portion 13 of the hook is given the form of a truncated cone at its outer end, 90 and the extreme smaller end of this truncated cone portion is formed with a projection 17 whose outer edge is parallel with the end of the cone and which is bounded at one end by an abrupt shoulder 18 and at the other by a slot 19 which extends inwardly 95 toward the base of the cone, so as to constitute the point 20 of the hook proper at one extremity of the projection 17 and the outer end of the slot 19, and the throat 21 at the 100 inner end of said slot, the surface of the projection 17 constituting a continuation of the side of the truncated cone. The body portion 13 is formed with a cavity 22 for the reception of a bobbin case support 23 and 105 bobbin case proper, 24, and the surrounding wall of this cavity 22 in the outer edge thereof contiguous to the outer end of the truncated cone is rabbeted or formed with a groove 25 for the reception of an annular 110 circumferential flange 26 formed on bobbin case support 23, thus giving the bobbin case a support and journal bearing within the body 13 of the hook and holding the case 115 rigidly against lateral movement lengthwise of the axis of rotation of the hook in one direction. It is held against lateral movement in the opposite direction by an inwardly 120 projecting annular flange 27 formed on the outer end of a cap 28, shown in detail in 125 130

Fig. 7, whose interior is complementary in shape to the exterior of the body 13 of the hook and fits accurately thereover and preferably against or close to the surface of ring 10 and the outer surface of the cap 28 is tapered or given the form of a truncated cone like the outer end of the body 13, the cap being held in place on the body 13 by any suitable means, such as screws 29. The flange 27 is of the same thickness or depth as the shoulder 18, so that the outer edge of the projection 17 which together with point 20 constitutes the hook proper, will be flush with the outer vertical surface of the flange 27, leaving no obstruction for the thread to catch upon, but where the projection 17 occurs the flange 27 is omitted or cut away and it does not begin again in the circle until the point 30 is reached, but the inner edge 20 or circumference of the projection 17, 20 is provided with a flange 31 which overlaps the flange 26 and constitutes a continuation of the flange 27, and between the slot 19 and the point 30 the edge of the cap 28 is cut away to form the needle clearance 32, and one end of this needle clearance is formed on an oblique shoulder 33 which extends inwardly from the shoulder 18 to the inner end of the slot 19 and from the inner end of the shoulder 33 the cut is carried outwardly along the bottom edge of slot 19, as shown at 34, so as to avoid covering the slot. The shoulder 33 is rounded or eased off toward the surface of the hook proper, 17, 20, as better shown at 35, in Fig. 19, so as to avoid the possibility of undue friction or abrasion of the inner strand 36 of the thread.

The cavity 22 in the body of the hook is sufficiently larger than the inner side of the bobbin case support 23 to afford ample room for the passage of the thread between said support and the body of the hook without danger of pinching or abrading the thread or compelling the thread to force any of the parts aside to enforce its passage between them, and the upper side of the flange 26 is cut away to form a notch or thread seat constituted by two shoulder 37, 38, the former of which at least is rounded to avoid abrading the thread, and between which shoulders the needle thread passes, as clearly shown in Figs. 17, 19 and 20, and this loop which is caught by the hook proper, 17, 20, is gradually forced into the throat 21 and carried 50 downwardly in the manner indicated in Figs. 16, 17 and 19, and forced over and around the bobbin case support 23, whose inner side or back is also tapered or of truncated cone shape to encourage the passage of the thread thereover, and by thus continuing around the under side of the bobbin case support while in the throat 21 it will be seen that it completely encompasses said support after being finally drawn up by 65 the takeup, or other suitable means, without

having forced its passage by pushing any of the parts aside or coming into abrasive contact with any of the mechanism or lubricated surfaces.

The bobbin case support 23 is held against rotation with the hook 13, 17, by any suitable means, but preferably by means of a curved finger, which will now be described, and which serves the twofold purpose of thus holding the bobbin case support and of removing the twist from the loop, which is the inevitable result of passing the loop around the bobbin case. This finger is shown in the form of a curved horn which is formed on the outer side of bobbin case support 23 near the top and conjoins with said member 23 by an easy curve or incline 39, so as to avoid catching the thread, and it thence curves inwardly to form a C-shaped finger 40, it being curved upwardly 80 as well as inwardly from its starting point on the member 23, and the extremity of this finger 40, which is tapered, terminates contiguous to a passage 41 formed in the top of member 23 for the needle, this passage being located at the outer side of the flange 26 in a lip or overhang 42 on the top of the member 23, and which is eased off gradually until it meets the main portion of said member 23 so as to avoid catching the 90 thread, the point of the finger 40 being situated considerably above this lip 42, as shown in Fig. 20. When the point 20 of the hook catches the loop and carries it downwardly, as better shown in Fig. 19, the inclination of the slot 19 carries one side of the loop inwardly to the back of the bobbin case support 23 and the conical formation of the surface of the hook, producing the shedding action on the other side or fold of the loop, carries the latter outwardly, and consequently puts a twist or half turn in the loop, but as the loop is drawn upwardly around the under side of the bobbin case support and pulled away from the hook 20, 100 it slides over the curved horn or finger 39, 40, and it is readily seen that this finger acts to bring that side of the loop which was behind the bobbin case support, outwardly to the front, and before it leaves the point 110 of the horn or finger 40 it is turned completely around to the position which is formerly occupied before the hook entered it, and consequently is untwisted. (See Figs. 20, 21.) To utilize the horn or finger 39, 40, 120 for preventing the rotation of the bobbin case support it is simply necessary to provide a yoke or stop which engages loosely around the finger with sufficient play to allow the loop to pass freely over the latter. 125 This yoke or stop is in the form of a bar 43, which is better shown in Fig. 1, and is curved upwardly across the front side of the bobbin case, and, as shown in Fig. 2, has an outward bend or cove, 44, in which 130

the finger 40 is situated. This bar 43 is held in place by two screws or other means, 45, 46, which are threaded in the ring 6, and in order that they may also serve as a means 5 of holding the bearing ring 10 in place, they are provided with shoulders which overlap the edges of this bearing ring. These shoulders are shown as being constituted by sleeves 47, through which the 10 screws are inserted and which serve the further useful purpose of holding the bar 43 outward away from the bobbin case.

The bobbin case support 23 is in the form of an annular shell open at the front, but 15 which may or may not be closed at the back. In this example of the invention it is shown as being provided at the back with a mere cross bar or web 48 to close the back of the bobbin case proper 24, and its interior is 20 adapted to receive the said case 24, which carries the bobbin 49 of any suitable construction, or, in fact, which carries any other suitable form of supply of lower thread. In this example, the bobbin is of the rotary 25 or spool form and journaled upon a pin 50 secured centrally within the bobbin case member 24, which is of cup-formation open at its inner end or side, so that when inserted into bobbin case support 23 the bobbin 30 will be completely housed and will be held against displacement inwardly by the cross bar or web 48. The bobbin case member 24 shown in this exemplification of the invention is of peculiar form, but does not 35 concern the present invention and will be described herein only generally as it constitutes the subject matter of the claims of a co-pending application, Serial No. 186,594, issued September 21st, 1909, No. 934,869, 40 and, indeed, so far as the present invention is concerned, is desirable rather than necessary. One side of the bobbin case member 24 is cut away, as shown at 51, Fig. 15, to form clearance for the thread and needle, 45 and the end wall of the case opposite this cutaway 51 is forced outwardly to form a tongue 52, against which lies a tension spring 53 of any suitable form, the tongue 52 having a slot 54 for the passage of the 50 thread from the bobbin, whence the thread passes between the tongue and spring 53 and emerges through notch 55 in the end of the spring, and thence passes upwardly within the curl of the horn or finger 40 and through 55 the throat plate. The spring 53 is held in place by a tension adjusting screw 56 screwed into the outer end of the bobbin case 24 and the spring is held against rotation by two branches 57 having their ends slightly 60 countersunk in the face of the case 24.

The bobbin case member 24 is locked in member 23 by a pivoted latch 58 having a projection 59 extending through the side of the bobbin case 24 and adapted to engage 65 in a slot 60 in the inner wall of bobbin case

support 23, the case member 24 having an aperture 61 through which emerges a projection 62, by which the bolt or latch 58 is operated.

63 is a guide or projection on case member 70 24 adapted to be received in a notch 64 in the outer end of case member 23, thus compelling the parts to go together properly.

Although the bobbin tension is arranged 75 against the outer face of the bobbin case, and therefore affords a straight run for the bobbin thread upwardly, the upper thread is nevertheless subject to considerable abrasion where it passes between the throat plate and the lower thread, and is then subjected to considerable strain, especially under high speed, when the takeup acts to pull it through the throat plate. In order to avoid this objectionable strain and 80 possible breaking of the upper thread, the bobbin is caused to pay out sufficient slack of the lower thread to allow the takeup to pull the upper thread without any resistance, or any material resistance, from the 85 bobbin thread. This is accomplished by journaling the bobbin case eccentric to the journal of the hook, so that the bobbin case will be given a bodily rising and falling movement while the hook revolves around it, 90 the falling movement being produced while the hook is coming down with the loop, thereby unwinding sufficient slack of the 95 bobbin thread at a point below the throat plate to allow the loop to be pulled up 100 during the next stitch without subjecting the thread to strain, the rising movement of the bobbin and case taking place while the loop is being pulled upwardly by the action of the takeup. This eccentricity of 105 the bobbin case is illustrated in Figs. 3 to 9, inclusive, and it is provided for by simply making the journal bearing for flange 26 eccentric to the journal bearing for the journal 12, or eccentric to the center of the 110 interior periphery of ring 10. In this example of the invention the hook is adapted to revolve from the operator, and with the invention thus described it will be seen that as the needle comes down and throws out 115 a loop of the needle thread on its inner side, the hook 20 enters said loop and carries it away from the operator and outwardly over and around the other side of the bobbin case support 23 the lower half or fold 36a of 120 the loop being first pulled inwardly under the hook 17, 20, and across the end of the shoulder 37, while the outside half or strand 36 of the loop is carried backwardly by the inclined slot 19 toward the back of the bobbin case support 23, at the point where it passes through the throat 21, but farther up the thread is forced outwardly, as shown in Fig. 19, by the shedding action of the 125 conical hook 17, 20, and cap 28. This strand 130

or half 36 of the loop at the commencement or time that the hook 20 first enters the loop, is what might be termed the inner side or strand of the loop, but as the hook 20 continues to revolve and this side 36 is shed outwardly away from the needle it finally becomes the outer side or strand in the act of passing around and under the bobbin case, and in this way gets the objectionable twist, or half turn, in the loop, which is removed subsequently by the curved horn or finger 39, 40, as before described, as the loop comes up the near side and is pulled away from the hook 20 by the takeup, or other means, in the manner shown in Figs. 20, 21, the hook 20 being revolved at its slowest speed at this time, which is accomplished in the ordinary manner (not shown) and in a manner usual with sewing machines of this character. It will also be seen that the presence of the wall or plate 6 and the close relation of the back of the hook body 13 to said wall, or parts connected with the wall, absolutely preclude the possibility of either of the threads becoming wound around the shaft 5, or any parts connected therewith, or with the hook, and there is nothing at the front side of said plate or wall that could act in any way to catch and entangle either thread, and this is true, even though the machine be rotated in the wrong direction or be operated without goods under the needle.

Having thus described my invention, what I claim as new therein and desire to secure by Letters Patent is:

1. In a rotary sewing machine, the combination of means for holding the supply of lower thread, means for throwing out a loop of the upper or needle thread, means for taking said loop around said supply of lower thread and imparting a turn or twist thereto, and means for untwisting said loop as it is drawn upward.

2. In a rotary sewing machine, the combination of means for holding the supply of lower thread, means for throwing out a loop of the needle thread, means for taking the inner side or fold of said loop downward and outward around said supply, means for thereafter drawing said loop upward and means for throwing the then inner or originally outer side of said loop outward to untwist it as it is drawn upward.

3. In a rotary sewing machine, the combination of means for holding the supply of lower thread, means for throwing out a loop of the needle thread, means for taking said loop around the said supply and imparting a turn or twist thereto, an in-turned finger and means for drawing the loop over said finger for removing said twist therefrom.

4. In a rotary sewing machine, the combination of means for holding the supply of lower thread, means for throwing out a

loop of the needle thread, means for taking said loop around the said supply and imparting a turn or twist thereto, an in-turned curved hook-shaped finger and means for drawing the loop over said finger for removing said twist therefrom.

5. In a rotary sewing machine, the combination of a support for a supply of lower thread, means for throwing out a loop of the needle thread, means for taking the said loop downward and shedding the inner fold thereof outward around said support, means for thereafter drawing the loop upward and an inturned finger over which the loop is drawn upward for removing the twist therefrom, said finger also serving to hold said support against rotation.

6. In a rotary sewing machine, the combination of a support for a supply of lower thread, means for throwing out a loop of the needle thread, means for taking said loop downward and shedding the inner fold thereof outward around said support, means for thereafter drawing the loop upward and a finger on said support curved outwardly therefrom and thence inwardly over the edge thereof for untwisting said loop as it is drawn upward.

7. In a rotary sewing machine, the combination of a support for a supply of lower thread, means for throwing out a loop of the needle thread, means for taking said loop downward and shedding the inner fold thereof outward around said support, means for thereafter drawing the loop upward, an inwardly curved finger on said support over which said loop is drawn for removing the twist therefrom, and a stop loosely engaging said finger for holding said support against rotation.

8. In a rotary sewing machine, the combination of a thread case, a rotary hook, and a journal bearing therefor, a non-rotary lower thread case support having a projecting flange constituting a journal for said case and a bearing in said hook for said support journal arranged eccentric to the said journal bearing of the hook.

9. In a rotary sewing machine, the combination of a hook support comprising a fixed apertured plate, a hook having a journal situated in the aperture of said plate, a flange removably secured to one end of said journal and overlapping the back of said plate for holding said hook in place, and means operatively connected with said journal for rotating said hook.

10. In a rotary sewing machine, the combination of a hook support, comprising a fixed apertured plate, a hook fitted closely to the face of said plate and having a journal fitting in the aperture thereof, the body of the hook overlapping the plate to close the space between the edge of the plate and the journal, a flange secured to the end of

said journal directly engaging and overlapping the back of said plate for holding said journal against axial movement, a shaft for rotating the hook and an operative connection between the shaft and the said journal.

11. In a rotary sewing machine, the combination of a hook support comprising a fixed plate or wall having an aperture therethrough and a countersink in the face thereof, and a second plate seated in said countersink and having an aperture constituting a journal bearing, a hook fitted immediately against the face of said second plate and having a journal arranged in the aperture thereof, a removable flange fitted against the back of said second plate and secured to said journal, a lower thread case around which said hook revolves, and means holding said second plate in said countersink and also holding said thread case against rotation.

12. In a rotary sewing machine the combination with a hook shaft and a revolving hook, of a hook support in which the hook is journaled independently of the shaft, an operative connection between said shaft and hook, and a fixed continuous wall interposed between the back of the hook and the shaft and said operative connection.

13. In a rotary sewing machine the combination of means for holding the supply of lower thread, means for throwing out a loop of the upper or needle thread, a revolving hook for taking said loop around

said supply of lower thread and imparting a turn or twist thereto, and means for subsequently untwisting said loop.

14. In a rotary sewing machine, the combination of a hook support comprising a fixed apertured plate, a hook having a body portion provided with a reduced extremity to form a circumferential shoulder, said reduced portion being journaled in the aperture with the shoulder adjacent one face of the plate, the extremity of the reduced portion being substantially flush with the other face of the plate, a flange removably secured to the extremity and overlapping the said other face of the plate, and means operatively connected to the said reduced portion for rotating the hook.

15. In a rotary sewing machine, the combination of a hook support comprising a fixed apertured plate, a hook having a body portion provided with a reduced extremity to form a circumferential shoulder, said reduced portion being journaled in the aperture with the shoulder adjacent one face of the plate, the extremity of the reduced portion being substantially flush with the other face of the plate, a flange removably secured to the extremity and overlapping the said other face of the plate, a crank pin carried by the flange, and a crank loosely engaging the pin for rotating the hook.

CHRISTOPHER WINKEL.
